D. A. SHEELER

REMOVABLE MOLD FOR CONCRETE WALLS

Filed June 15. 1921

UNITED STATES PATENT OFFICE.

DANIEL AUSTIN SHEELER, OF GRANTON, WISCONSIN.

REMOVABLE MOLD FOR CONCRETE WALLS.

Application filed June 15, 1921. Serial No. 477,800.

To all whom it may concern:

Be it known that I, DANIEL AUSTIN SHEELER, a citizen of the United States, and resident of Granton, in the county of Clark and State of Wisconsin, have invented a certain new and useful Removable Mold for Concrete Walls, of which the following is a specification.

This invention relates to improvements 10 in molds for forming concrete walls for buildings, more specifically, to that class of molds which are employed in building double walls with an air space between them; and in that class of forms or molds 15 in which the mold members are moved upwardly as the walls are constructed. In this method the molds usually comprise a series of parallel and horizontally arranged plates or boards spaced apart a distance 20 equal to the thickness of the wall members, and of a depth from one to two feet. These members are first placed adjacent to the ground surface and then filled with concrete. After the concrete has set, the mold members 25 are moved upwardly with their lower edges adjacent to the top edge of the wall, thus providing space between the members which may again be filled with concrete.

The plates are usually held in position 30 relative to each other by means of blocks placed between the members and wires to tie them together. This is a very awkward and expensive way of mounting the plates, and it is therefore the object of my invention 35 to provide new and improved means for mounting the plates so they may be easily and quickly moved to their new position.

A still further object is to provide in a 40 movable mold for forming double concrete walls having parallel and horizontally arranged mold members, improved means for mounting the mold members so they may be easily and quickly disengaged from the walls, and also provide means whereby the 45 said parallel mold members may be adjustably mounted relative to each other.

These and other objects will be apparent to those skilled in the art.

50 My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of a segment of my improved mold construction showing the manner in which it is applied to a wall.

Figure 2 is a transverse sectional view 60 of the same taken on the line 2—2 of Figure 1.

Figure 3 is a plan view of one of the mold supporting frames.

Figure 4 is a detail view of a modified 65 form of one of the frame members.

Figure 5 is a detail plan view showing the manner in which one of the mold members is provided with means for forming the upper roof portion of the end walls of 70 a building.

I have used the reference numeral 10 to indicate the walls of a building which are mounted parallel to each other and spaced apart a slight distance so as to provide an 75 air space between them.

The numeral 11 indicates mold plates which are placed adjacent to the outer edges of each of the wall members 10 with their lower edges adjacent to the upper edge of 80 the wall members 10 so that the said plates may be filled between them for the purpose of increasing the height of said members.

For securing these plates 11 in position, I have provided a series of brackets which 85 are spaced apart at equal intervals along the entire length of the wall in which the plates extend. This frame comprises a series of vertical members 12 placed adjacent to the outer face of each of the plates 11, the said plates being secured in position by means of lugs 13 which extend into dove tailed grooves 14 on the inner edge of each of the members 12, as clearly shown in Figure 2.

These lugs 13 may be of any desired 95 length, preferably three or four times the width of the member 12 so that the said members 12 may be attached or detached by simply moving them longitudinally with the members 13.

The members 12 extend above the upper edges of the plate a considerable distance. Each of the inner members 12 is slightly spaced apart and pivotally connected to a 105 horizontally and transversely arranged link 15 which is placed a slight distance above the upper edges of the plates 11. The outer members are each pivotally connected to the same bar 15 by means of bolts 16 in any one 110 of a series of openings 17, said openings being arranged so that the said outer members 12

may be adjusted toward or from the inner members.

The upper end of each of the members 12 is pivotally connected to one end of a lever 18 by means of a bolt 19, said bolt being designed to be mounted in any one of a series of openings 20 in the said lever, the said levers 18 being mounted in a substantially horizontal position when the device is applied to a wall, one of the said levers being arranged to rest adjacent to one side of the members 12, while the other lever is designed to rest adjacent to the opposite side of said members and the said levers extend ed in opposite directions. The outer end of each of the said levers is provided with a handle 21.

Slidably mounted between the inner members 12 and parallel therewith, I have provided a bar 22, the upper end of which is pivotally connected to the central portion of each of the levers 18. The bar 22 is of a length equal to the inner members 12, and has provided at its lower end a plate 23 adjacent to each of its sides so as to overlap the inner edges of the members 12. These plates form a guide for holding the member 22 in proper alinement. Each of the edges of the member 22 near its lower end is formed inclined inwardly until they reach a point beneath the plates 23. The edges then are inclined outwardly so that a head 24 is formed on the lower end of said member 22, as clearly shown in dotted lines in Figure 2. This head is designed to rest normally adjacent to the inner edges of the lower ends of the inner members 12, the head being of a width equal to the width of the upper end of the bar 22, and when the said head 24 is so spaced the inner members 12 are parallel with each other.

By moving the handle portion of the levers 18 downwardly, it will be seen that the bar 22 will be moved downwardly which will cause the head 24 to be moved down below the lower ends of the adjacent members 12 to a position as shown in extended dotted lines. This will permit the inner lower corners of the members 12 to rest against the narrow portion of the member 22, said portion being indicated by the numeral 25, thus permitting the lower ends of the inner members 12 to swing inwardly about the pivot members in the bar 15, and the inner plates 11 to disengage their respective wall members 10.

This downward movement of the free end of the levers 18 will also cause the upper ends of the outer members 12 to be swung inwardly a slight distance, thereby causing the lower ends of said outer members to be moved outwardly as the bars are swung about the bolts 16 and the outer plates 11 to disengage the outer faces of the walls 10.

The frame members together with the plates 11 may then be easily and quickly moved upwardly until their lower edges rest near the upper edges of the wall members, after which the levers 22 are elevated. This will cause the lower ends of the outer members 12 to move inwardly and the head 24 to be moved upwardly, which will cause the lower ends of the inner members 12 to be moved outwardly.

For locking the upper ends of the outer members 12 outwardly and the lower ends inwardly, I have provided notches 26 on the inner edges of said outer members 12, each of said notches being designed to receive a pivoted pawl member 27 which is pivoted to the bar 15 by means of a bolt 27^a, this bolt being mounted in any one of a series of openings 28. The said bar 27 is provided with a series of openings 29 designed to receive a bolt 30 through which is pivoted one end of a toggle lever 31, the said toggle 31 being arranged to lock the plates 27 in position in the notches 26, as clearly shown in Figure 2.

When it is desired to release the bars 27, the operator grasps the central portion of the toggle 31 which he elevates and which in turn moves the upper ends of the members 27 inwardly until they disengage the notches 26. The levers 22 and the bar 18 may then be operated as before described.

By providing the openings 20, 17 and 28, I have provided means whereby the outer members 12 may be adjusted to form walls of different widths.

When the members 12 have been placed outwardly from the position shown in Figure 2 by placing the bolts 16 and 19 into other openings, it will be seen that the upper ends of the members 17 will not engage the notches 26, so I have provided openings 28 to permit the bolts 27^a to be moved outwardly a distance equal to that in which the members 12 are moved outwardly. The bolts 30 are then removed and placed into other openings 29 closer to the bolts 27^a which provides also for the outward adjustment of the members 27, and at the same time enables the operator to use the same toggle member 31.

In building foundations, it is often desirable to make one or both of the wall members 10 considerably thicker than the wall portion above the foundation. This can, of course, be accomplished by adjusting the bolts before described. When it is desired to build the upper wall narrower than the lower wall, the outer members 12 may be set closer together.

In order to make a uniform offset in the outer face of either of the walls, or both, between the upper and lower wall portions, I have provided extra outside members 12 having a bent portion 32 which terminates

into a portion 33 parallel with the upper portion 31^a, this device being clearly shown in Figure 4. Suitable bent plates 34 are substituted for the plates 11. The bar 31^a 5 may be substituted for one of the outer bars 12. After the offset portion of the wall has been constructed, the outer members 12 may be again replaced.

For forming the upper edges of the end walls to conform with the slant of the roof, I have provided openings 35. These openings are arranged in inclined rows at each of the members 11. These rows are of the same pitch as the roof to be constructed. 10 Each of the openings of the single row is designed to receive a rod 36 which extends between two mold members used to form each side of the wall, as clearly shown in Figure 5, and serves the purpose of forming a guide for the mason when the concrete is being poured between the said molds. The concrete is poured so as to aline with the said rods, after which the rods may be removed when the concrete has set slightly and the 15 said inclined upper edge may then be troweled smooth if so desired.

By this arrangement, it will be seen that I have provided means whereby the proper inclination to the upper edge of the roof portion of the walls may be easily and quickly formed as the concrete may be poured between the rods.

By this arrangement, it will be seen that I have provided a clamp frame for wall molds 20 which may be easily and quickly applied, and when applied will be rigidly held in position, and also which is capable of being adjusted to walls of different widths.

I claim as my invention:

40 1. A clamp for cement molds comprising spaced inner and outer clamping bars, a bar arranged across the central portion of all of the said bars, means for pivoting said inner bars to said cross bar, and means for pivotedly and adjustably connecting said outer bars to the outer ends of the said cross bar, a lever adjustably pivoted to one end of each of said outer bars, the said levers being arranged in overlapping relation with 45 each other and substantially parallel to said cross bar, a slide bar mounted between said inner bars and pivotedly connected to the central portion of both of said lever bars, the opposite end of said slide bar being tapered and provided with an enlarged head, guide members adjacent to each side of said head, locking bars adjustably and pivotedly mounted on said cross bar, a toggle bar pivotedly and adjustably mounted between 50 both of said locking bars, the said locking bars being designed to engage notches in the outer clamping bars when in one position of their movement.

2. A mold for constructing double concrete walls comprising inner and outer sets 55

of parallel and horizontally arranged plates, a series of vertically arranged clamping bars detachably connected to the outer faces of each of the outer plates, a series of vertically arranged clamping bars detachably connected to the inner face of each of the inner plates, all of said clamping bars being provided with upwardly projecting ends above said plates and arranged in transverse groups, a transverse bar pivotedly connected to each set of inner clamping bars, means for adjustably pivoting each of the outer clamping bars to an adjacent end of said transverse bar, a lever adjustably and pivotedly connected to the upper end of each of the said outer clamping bars, said levers being arranged in overlapping relation to each other and substantially parallel to said transverse bar, a slide bar mounted between said inner clamping bars and pivotedly connected to the central portion of both of said lever bars, the lower end of said slide bar being provided with an enlarged head for engaging the inner edges of the free ends of said inner clamping bars while in one position of its movement, and inclined locking bars pivotedly and adjustably mounted to said transverse bar, a toggle bar pivotedly and adjustably mounted to said toggle bars, said locking bars being designed to engage notches in said outside clamping bars for locking them in position 60 parallel with each other.

3. A mold for constructing concrete walls comprising spaced parallel plates, a detachable and adjustable frame member for supporting said plates in operative position relative to each other, each of said plates being provided with a series of openings, the said openings of one plate corresponding with those of the opposite plate and being arranged in rows, the said rows corresponding to the inclination of the standard pitch of the roofs, a rod detachably mounted in corresponding openings of a given row of 65 openings.

4. A mold for constructing double concrete walls comprising inner and outer sets of parallel and horizontally arranged plates, each set of said plates being provided with detachably and transversely arranged rods between them, said rods being arranged in inclined planes corresponding with the standard pitch of roofs, a series of vertically arranged clamping bars detachably connected to the outer faces of each of the outer plates, a series of vertically arranged clamping bars detachably connected to the inner face of each of the inner plates, all of said clamping bars being provided with upwardly projecting ends above said plates and arranged in transverse groups, a transverse bar pivotedly connected to each set of inner clamping bars, means for adjustably pivoting each of the outer clamping bars to 70 75 80 85 90 95 100 105 110 115 120 125 130

an adjacent end of said transverse bar, a lever adjustably and pivotedly connected to the upper end of each of the said outer clamping bars, said levers being arranged in overlapping relation to each other and substantially parallel to said transverse bar, a slide bar mounted between said inner clamping bars and pivotedly connected to the central portion of both of said lever bars, the lower end of said slide bar being provided with an enlarged head for engaging the in-

ner edges of the free ends of said inner clamping bars while in one position of its movement, and inclined locking bars pivotedly and adjustably mounted to said transverse bar, a toggle bar pivotedly and adjustably mounted to said toggle bars, said locking bars being designed to engage notches in said outside clamping bars for locking them in position parallel with each other.

15

DANIEL AUSTIN SHEELER.
